LINE TRANSPOSITION BRACKET WITH
REINFORCING GUSSETS

Rogers Case, Orange, N. J.

Application June 21, 1951, Serial No. 232,738

6 Claims. (Cl. 174—147)

1

This invention relates to a bracket for transposing paired line wires of communication lines.

Specifically considered the disclosure herein relates to an improvement in the brackets disclosed in my issued Patents No. 2,455,228, dated November 30, 1948 and No. 2,455,229, dated November 30, 1948, both of which patents relate primarily to transposition brackets cast of a "light" metal such as aluminum and aluminum alloys, magnesium and magnesium alloys. As explained in those patents, it is a matter of necessity in the more efficient systems of long distance electrical communication along wires that paired wires be transposed at intervals by crossing them and the brackets disclosed in those patents are constructed easily and accurately to effect such transposition. Also as explained in those patents, it is of great assistance in making the transposition that the insulators on which the wires are trained be mounted rotatably in four outwardly open clevises in which the insulator pins are supported.

In service there is a very substantial pressure of the wires against the structure of the brackets and such pressure creates the problem of providing brackets of adequate strength with economy in the weight of metal included in the bracket and the provision of brackets so light as to facilitate their installation in the line.

The object of my invention is therefore to provide transposition brackets primarily in accordance with the disclosure of the above-noted patents, which brackets exert a maximum resistance to the stress-creating thrust of the wires transposed by the bracket in conjunction with the inclusion of a minimum weight of metal in the bracket.

I have discovered that this object is attained by adding a minimum weight of metal in a particular form and position in the structure of the bracket and have proved by experiment the benefits derived from such minimum addition of metal.

As illustrated specifically herein, the improvement of my present invention is shown as applied to the bracket disclosed in my prior Patent No. 2,455,228, which is a bracket of the "span" type. That is, it is purposed particularly for insertion in an electrical line between the line poles. As indicated above, the improvement of this invention is equally applicable to the bracket of my prior Patent No. 2,455,229, which is purposed particularly for direct mounting on the cross arm of a line pole.

In the accompanying drawings, illustrative of one embodiment of my invention:

2

Fig. I is a plan view of my improved transposition bracket.

Fig. II is a cross sectional view taken in the plane of the section line II—II of Fig. I and looking toward the upper edge of the sheet of drawings.

Fig. III is an end elevation of the bracket frame structure as seen at the lower end of the bracket as shown in Fig. I and looking toward the upper edge of the sheet of drawings which carries Fig. I, the spool-form insulators of the complete bracket assembly being omitted from the illustration.

Fig. IV is a side elevation of the bracket frame structure as shown in the preceding figures of the drawings, viewing the bracket frame from the right in Fig. I and omitting the insulators shown in that figure of the drawings.

Referring to the accompanying drawings, the frame of the bracket consists primarily of end reaches 1 and 2 and side reaches 3 and 4. Each of the end reaches 1 and 2 has a plane portion 5 which defines the median, or base, plane of the frame. Looking to the right of the end reach 1 of the frame as it appears in Figs. I and II, the structure of the frame is deflected downwardly to form the lower fork 6a of a clevis 6 the upper fork 6b of which is connected by angularly extended leg 6c with the median base portion 5 of the reach. To the left of Figs. I and II the structure of end reach 1 of the bracket is deflected upwardly to provide the upper fork 7b of clevis 7 and the lower fork 7a of the clevis is joined with the median plane or base 5 of the reach by angularly extended leg 7c.

Clevises 8 and 9 bear respectively the same relation to the end reach 2 as do clevises 7 and 6 to end reach 1. Thus the lower fork 8a of clevis 8 is connected by an angularly extended leg 8c with the median or base portion 5 of end reach 2 and upper fork 8b of clevis 8 is deflected upwardly from the horizontal plane of that region. The upper fork 9b of clevis 9 is connected by angular leg 9c with the base portion 5 of end reach 2 and the lower fork 9a is deflected downwardly from that base plane.

Side reach 3 blends with the lower fork 6a of clevis 6 and the upper fork 8b of clevis 8 appearing in Figs. III and IV of the drawings. Side reach 3 is thus angularly disposed with respect to a horizontal plane, rising from the lower fork of clevis 6 to the upper fork 8b of clevis 8.

Similarly, the upper fork 7b of clevis 7 blends with side reach 4 which also is angularly disposed with respect to the horizontal plane of the bracket, declining from the upper fork of clevis 7 to the lower fork 9a of clevis 9, or conversely rising

from the lower fork of clevis 9 to the upper fork of clevis 7.

Spool-form insulators 10, 11, 12 and 13 are mounted respectively in clevises 6, 7, 8 and 9. Desirably as is shown in the drawings, insulator pins 14 are of such form that the insulators are freely rotatable on them. These insulators which are of primarily spool-form and which may be composed of glass, porcelain, rubber, fiber or plastic composition or other material having suitable physical and electrical-insulating properties are carried each by its insulator pin 14 which has a head 14a resting on the upper fork of the clevis and a shank 14b which projects below the under-fork of the clevis. Suitable means for engaging the insulator pin in the clevis in which it is mounted is shown as a cotter pin 14c, but such engagement may be provided by means of a nut having threaded engagement with the projecting end of the pin or by any other suitable engagement.

In the arrangement of the insulators it will be seen that insulator 10 has its wire-receiving groove 16a above the base, or median, plane of the bracket frame and that the wire-receiving groove 11a of insulator 11 lies below the base, or median, plane of the frame. The wire-receiving grooves of insulators 13 and 12 are in vertical alignment with the wire-receiving grooves of insulators 10 and 11 respectively.

It will be seen that the arrangement of the clevises and insulators mounted in them is diagonal. Thus the high clevises 6 and 9 are diagonally opposite each other in the bracket assembly and the low clevises 7 and 8 similarly are diagonally opposite each other. As viewed in the drawings, the high and low clevises, and insulators mounted in them are staggered relatively in the bracket. This arrangement conforms to the crossing of line wires within the bounds of the bracket frame. Together with the fact that all the clevises open outwardly of the frame structure, it conforms to the operation of threading the paired line wires on the insulators of the bracket without interrupting the span or disassembling the bracket.

In the relation of the paired line wires with the bracket, the wire A is shown as trained on the low insulators 11 and 12 and the wire B is shown as trained on the high insulators 10 and 13. In their crossed relation the two wires are spaced vertically a distance equal to the distance between the wire-receiving grooves of the diagonal pair of high insulators and the wire-receiving grooves of the diagonal pair of low insulators, as for example the vertical distance between the wire-receiving grooves 10a and 11a in Fig. I of the drawings. Because the insulators are mounted in the clevises, the wires trained on the insulators in their wire-receiving grooves are confined within the clevises. There is therefore no likelihood that there will be a "floater," that is an upwardly escaped wire, if an insulator should be broken in service.

The entire frame structure of the bracket being a one-piece casting possesses in a very high order the properties of rigidity, strength and endurance. The clevises being integrated in the frame structure by casting, there are no bolts or rivets to shear or work loose in service and the insulator pins are supported in clevises which minimize spring or other relative movement between parts or regions of the structure. The insulator pins are thus protected against the thrust

of the line wires on the insulators which are mounted on them.

As to the vertical spacing between the line wires in their crossed relation, that vertical spacing is modified by deflecting the lower fork of each of the clevises for the high insulators slightly below the base plane of the frame and by elevating the upper forks of the clevises for the low insulators slightly above the base plane of the frame. This accommodation in the organization of the frame permits the use of insulators having a desirable structural contour while obtaining a desired spacing of the wires. That is, a desirable form of insulator having been selected, the frame of the bracket can be cast to give a determined vertical spacing of the crossed wires while using insulators of the specific selected form, by casting the one-piece frame with the forks of its clevises deflected appropriate distances from the base plane of the frame.

As indicated above, it is desirable that the bracket as described be integrally cast of one of the "light" metals such as aluminum or an aluminum alloy, magnesium or a magnesium alloy. Of these I have found aluminum alloy to be preferable. Also as above indicated, I have found that a slight additional mass of metal placed most advantageously in the structure of the bracket adds stress resistance far out of proportion to the added weight.

Such reinforcement consists of relatively thin, triangular ribs or gussets integrated between the median or base portions of each of the end reaches 1 and 2 of the bracket and along the adjacent surfaces of the longer angularly extended legs of the clevis-forming portions of those reaches. These triangular gussets 15 and 20 have relatively long free edges 15a and 20a so that they each integrate with the median portion of the reach and one of the angularly extended legs of a clevis throughout the major proportion of the length of those members. The gussets 15 and 20 have their edges approximately parallel so that with the included median portion of the reach, they form an approximately rhombic reinforcement extended between and integrated with the angularly extended legs of the clevis. As shown in Fig. II of the drawings this gusset structure comprising gussets 15 and 20 extends between the inner face of leg 8c of outwardly open clevis 6 and the inner face 1c of outwardly open clevis 7. Similarly, as shown in Fig. III of the drawings with respect to reach 2 of the bracket, gussets 16 and 17 are arranged with their free edges 16a and 17a approximately parallel and with the gusset structure standing between angularly extended leg 8c of outwardly open clevis 8 and leg 9c of outwardly open clevis 9. As with the gusset structure made part of reach 1, each of gussets 16 and 17 is integrated with the median portion 5 of the reach.

This relatively small mass of metal because of its position and its integration with the fundamental structures of the bracket, presents a maximum opposition to the thrust of the line wires transposed by the bracket and thus counteracts the stress-creating effects of such thrust. It has been found by test that the regions in which the stresses caused by the thrust of the wires are concentrated in a bracket lacking this reinforcement are adjacent the corners at which the forks of the clevises join the median portions of the reaches and particularly adjacent the junction of the longer angularly extended arm of the clevis with the median portion of the reach. With the

addition of the gusset structures failure takes place only at much higher load and at the holes for the insulator pins or adjacent such holes in the end reaches 3 and 4 of the bracket. It is to be understood that without such reinforcement the bracket as cast from a suitable aluminum alloy is amply able to sustain the normal load imposed by the line wires, which is about 2000 pounds. The reinforcement provided by the gusset structure does, however, give increased assurance against bracket failure under the exigencies of continued service. Also, the reinforcement to the brackets gives assurance against disruption of the line by bracket failure under abnormal conditions, such as unusually high wind pressures and abnormal accumulations of ice on the brackets.

To determine the resistance of the fundamental bracket structure to the load imposed by the line wires and to show comparatively the increase in such resistance obtained by adding the gusset structure of this invention, tests were made on three types of the bracket as follows:

Type A.—This bracket was integrally cast from a suitable aluminum alloy, which metal specifically was Alcoa 356T6 alloy. It was close to the exact disclosure of Patent No. 2,455,228 comprising no reinforcing gussets as herein disclosed.

Type B.—This bracket was made of the same alloy as the type A bracket, and in its initial structure corresponded exactly to that bracket. This type B bracket was, however, reinforced by gussets shaped and arranged as herein disclosed. Those gussets were welded to the longer angularly extended legs of the clevises and to the median or base portions of the side reaches of the bracket.

Type C.—This bracket was identical with the specific disclosure herein, with the reinforcing gussets cast integrally with the fundamental structure of the bracket. It was composed of the same specific metal as the type A and type B brackets.

The fundamental structure of the type B bracket, like the type A bracket was obtained by permanent mold casting, and the entire structure of the type C bracket including the gussets was obtained by permanent mold casting as an initially integral structure. Type C is preferred to type B, primarily because the manufacture of the bracket is simplified by eliminating the step of welding.

For loading the brackets, the Baldwin-Southwark 300,000 pound test machine was used. In place of the standard glass insulators, aluminum replacements were used because it was found that the glass insulators failed before any damage occurred to the brackets. Two $\frac{1}{4}$ inch steel cable of approximately 8 foot length were attached to steel bars with the proper line spacing for the brackets to be tested and the cable tension was equalized by pivoting the upper bar at its center. The lower bar was pivoted at its center so that it was free to move in the opposite plane allowing the cables to twist if the loading resulted in that type of moment. The loading of all three brackets was carried to destruction. The data on the tests is as follows:

Type	Weight, pounds	Load at failure, pounds
A	1.36	2,800
B	1.41	3,850
C	1.41	3,900

The result of these tests was to demonstrate that the almost negligible mass of metal included in the gussets, in the case of the type B and type C brackets merely 0.05 lb. increased the sustainable loading of the brackets 1050 lbs. in one bracket and 1100 lbs. on the other. Although the increase in strength of the C type bracket over the B type is relatively small, it is much more economical to provide for the formation of the 10 gussets in the permanent mold than to make such gussets separately and to weld them into place after casting.

Whereas the primary intent of my invention is to reinforce the fundamental structure of a 15 transposition bracket frame made by the permanent mold casting of one of the light metals and by strengthening such frame to decrease the total weight of metal desirably included in the bracket, my invention may be utilized in brackets which are of the same form but which are 20 differently made. Thus gussets of the same shape as above described may be integrated in the same described positions in a bracket of the same described shape and structural arrangement 25 but which is fabricated of steel or other suitable metal instead of being integrally cast. In such brackets the gussets by reinforcing the structure of the bracket frame, serve similarly or to reduce the total weight of metal necessarily or desirably included in the bracket.

As used herein the terms "vertical," "lower," "higher," "end," "side" and the like refer to what may be considered the normal position of the bracket in a line the wires of which are transposed by the bracket in accordance with preexisting general practice. It is to be understood that the insulators either may rotate on their pins, they may be rotatable in the clevises or both the pins and the insulators may be rotatable with 35 respect to each other and to the frame structure of the bracket.

Having disclosed one embodiment of my invention, it is to be understood that changes in materials, structure and arrangement may be made 40 within the bounds of the invention as defined 45 in the statement of the claims appended hereto.

I claim as my invention:

1. A wire-transposing bracket adapted for the crossing of paired line wires comprising a frame 50 integrally cast from a light metal selected from aluminum, magnesium and their alloys and having two generally parallel reaches terminally forked at both ends of each by means of longer and shorter legs angularly extended from a central base region to provide four outwardly open insulator-mounting clevises, the longer and shorter legs of the clevises of each said reach being oppositely arranged and the arrangement of the said longer and shorter legs being reversed in the said two forked reaches to give a diagonal matching of higher and lower insulator-mounting clevises in the bracket frame, two reaches interconnecting the said two forked reaches, spool-form insulators having circumferential wire-receiving grooves rotatably mounted in the said four clevises; and two strengthening gussets 55 extended between and integrated with the longer legs of the said clevises of each forked reach and adjacent surfaces of the said base region thereof, said two gussets of each said reach being arranged in an approximately diagonal line relatively to each other to provide reinforcement in the structure of the bracket frame and composite stress resistance against the load imposed by 60 wires transposed by the bracket.

7
2. In a wire-transposing bracket adapted for the crossing of paired line wires, a frame integrally cast from a light metal selected from aluminum, magnesium and their alloys and having two generally parallel reaches terminally forked at both ends of each by means of longer and shorter legs angularly extended from a central base region to provide four outwardly open insulator-mounting clevises, the longer and shorter legs of the clevises of each said reach being oppositely arranged and the arrangement of the said longer and shorter legs being reversed in the said two forked reaches to give a diagonal matching of higher and lower insulator-mounting clevises in the bracket frame, two reaches interconnecting the said two forked reaches; and two strengthening gussets extended between and integrated with the longer legs of the said clevises of each forked reach and adjacent surfaces of the said base region thereof, said two gussets of each said reach being arranged in an approximately diagonal line relatively to each other to provide reinforcement in the structure of the bracket frame and composite stress resistance against the load imposed by wires trained on insulators mounted in the said clevises and transposed by the bracket.

3. A wire-transposing bracket adapted for the crossing of paired line wires comprising a frame integrally cast from a light metal selected from aluminum, magnesium and their alloys and having two generally parallel reaches terminally forked at both ends of each by means of longer and shorter legs angularly extended from a central base region to provide four outwardly open insulator-mounting clevises, the longer and shorter legs of the clevises of each said reach being oppositely arranged and the arrangement of the said longer and shorter legs being reversed in the said two forked reaches to give a diagonal matching of higher and lower insulator-mounting clevises in the bracket frame, two reaches interconnecting the said two forked reaches, spool-form insulators having circumferential wire-receiving grooves rotatably mounted in the said four clevises; and two strengthening gussets extended between and integrated with the longer legs of the said clevises of each forked reach and adjacent surfaces of the said base region thereof, said two gussets of each said reach being arranged in an approximately diagonal line relatively to each other to provide reinforcement in the structure of the bracket frame and composite stress resistance against the load imposed by wires transposed by the bracket.

4. In a wire-transposing bracket adapted for the crossing of paired line wires, a frame integrally cast from a light metal selected from aluminum, magnesium and their alloys and having two generally parallel reaches terminally forked at both ends of each by means of longer and shorter legs angularly extended from a central base region to provide four outwardly open insulator-mounting clevises, the longer and shorter legs of the clevises of each said reach being oppositely arranged and the arrangement of the said longer and shorter legs being reversed in the said two forked reaches to give a diagonal matching of higher and lower insulator-mounting clevises in the bracket frame, two reaches in-

5 terconnecting the said two forked reaches; and two strengthening gussets extended between the longer legs of the said clevises of each forked reach and adjacent surfaces of the said base region thereof and cast integral therewith, said two gussets of each said reach being arranged in an approximately diagonal line relatively to each other to provide reinforcement in the structure of the bracket frame and composite stress resistance against the load imposed by wires trained on insulators mounted in the said clevises and transposed by the bracket.

10 6. A wire-transposing bracket adapted for the crossing of paired line wires comprising a frame having two generally parallel reaches terminally forked at both ends of each by means of longer and shorter legs angularly extended from a central base region to provide four outwardly open insulator-mounting clevises, the longer and shorter legs of the clevises of each said reach being oppositely arranged and the arrangement of the said longer and shorter legs being reversed in the said two forked reaches to give a diagonal matching of higher and lower insulator-mounting clevises in the bracket frame, two reaches interconnecting the said two forked reaches, spool-form insulators having circumferential wire-receiving grooves rotatably mounted in the said four clevises; and two strengthening gussets extended between and integrated with the longer legs of the said clevises of each forked reach and adjacent surfaces of the said base region thereof, said two gussets of each reach being arranged in an approximately diagonal line relatively to each other to provide reinforcement in the structure of the bracket frame and composite stress resistance against the load imposed by wires transposed by the bracket.

15 7. In a wire-transposing bracket adapted for the crossing of paired line wires, a frame having two generally parallel reaches terminally forked at both ends of each by means of longer and shorter legs angularly extended from a central base region to provide four outwardly open insulator-mounting clevises, the longer and shorter legs of the clevises of each said reach being reversed in the said two forked reaches to give a diagonal matching of higher and lower insulator-mounting clevises in the bracket frame, two reaches interconnecting the said two forked reaches; and two strengthening gussets extended between and integrated with the longer legs of the said clevises of each forked reach and adjacent surfaces of the said base region thereof, said two gussets of each said reach being arranged in an approximately diagonal line relatively to each other to provide reinforcement in the structure of the bracket frame and composite stress resistance against the load imposed by wires transposed by the bracket.
